UNITED STATES PATENT OFFICE.

CHARLES B. THOMPSON, OF BUFFALO, NEW YORK, ASSIGNOR TO AMERICAN RADIATOR COMPANY, A CORPORATION OF NEW JERSEY.

STEAM-TRAP AND AIR-VENT FOR RADIATORS

No. 882,595.

Specification of Letters Patent. Patented March 24, 1908.

Application filed July 5, 1907. Serial No. 382,216.

To all whom it may concern:

Be it known that I, CHARLES B. THOMPSON, a citizen of the United States, and resident of Buffalo, county of Erie, and State of New York, have invented certain new and useful Improvements in Steam - Traps and Air-Vents for Radiators, of which the following is a specification, and which are illustrated in the accompanying drawings, forming a part thereof.

The invention relates to devices for preventing an excess of steam passing through heating radiators, while permitting the free discharge of air therefrom; and it consists of the structure hereinafter described and which is illustrated in the accompanying drawings, in which

Figure 1 is a detail of a radiator, the improved trap and vent being shown in longitudinal section; and Fig. 2 is an end elevation of the trap and vent.

Steam radiators require to be vented in order that when the steam is first turned on it may drive out the cold air with which the radiator is filled. The devices most commonly used for this purpose, whether automatic or manually controlled, vent into the room, and in addition to the objection that the air discharged is apt to be foul there frequently occurs an escape of water and of steam.

In the use of steam radiators it is desirable, in the interest of economy also, that the steam be retained in the radiator until it shall have wholly or in large part condensed, and this purpose has been usually accomplished when a very low pressure is maintained by providing a trap in the return pipe or nipple connecting it with the radiator, the water seal preventing the escape of the steam. When appreciable pressure is used this arrangement is inefficient because the water seal is broken.

The object of this invention is to provide, in a single device, an air vent and a water seal, and furthermore, to so vent the radiator that the air will be discharged into the return pipe without forcing same through a water seal; and to also supplement the usual water seal steam-trap with a spring-closed check valve, yielding to an accumulated head of water, provision being made for adjusting the tension of the spring for varying pressures and various sizes of radiators. By this means it becomes unnecessary to pro-

vide a manually-controlled valve at the discharge end of the radiator.

A section of a radiator is shown at 10, being the section from which the return pipe leads. A plug 11 is screwed into a suitable aperture at the base of the radiator section. This plug is cored to form a water sealed chamber 12, metal being saved by casting the plug with a boss or enlargement 13 on its inner end to provide ample stock within which to form the chamber. A port 14 is formed in the wall of the plug to connect the chamber 12 with the interior of the radiator, and the plug is so set that this port is at the lower side. A threaded aperture enters 70 through the outer face of the plug, into which there is screwed a nipple 15, this orifice entering the upper portion of the chamber so that there will be no discharge of water from the radiator until it has reached a 75 higher level than the port 14. An elbow 16 is attached to the nipple 15, preferably by means of a union joint 17, the discharge end 18 of the elbow being turned down and being internally threaded for the attachment of 80 the return pipe, not shown.

In the lower end 18 of the elbow is provided an annular downwardly-facing valve seat 19, to which is applied a disk valve 20 loosely fitting a rod 21, the upper end of 85 which is threaded and extends through a correspondingly threaded orifice at the top of the elbow, its end being transversely slotted for the engagement of a screw driver. The valve 20 is held to its seat by means of a 90 spring 22, reacting against its lower face and a pin 23 set through the lower end of the rod 21. By turning the rod 21 the tension of the spring 22 can be regulated.

A nipple 24 of small bore is set through the 95 wall of the plug 11, as shown through the upper wall of the boss 13, connecting the upper portion of the chamber 12 with the interior of the radiator. By thus locating the air vent away from the side wall of the radiator it is 100 not flooded by the water of condensation flowing down such wall, and by making it in the form of a nipple of substantial length it better retards the flow of steam after the air is expelled, as the slight lead of steam it will 105 accommodate is condensed in the passage. The water of condensation clogging the duct. This condensation is promoted by using for the nipple a metal of high conductivity, such as brass. A small duct 25 extends longitudi- 110

dinally into the rod 21, from its lower end and laterally, at a level above that to which the water will ordinarily rise, to communicate with the interior of the elbow 16. By 5 this means a constantly open air vent is provided through the nipple 24, the chamber 12, nipple 15, the upper portion of the elbow 16 and the duct 25 to the return pipe, so that when steam is turned into the radiator cold 10 air may slowly escape. The water of condensation accumulates at the base of the radiator, rising in the chamber 12 through the port 14 and overflowing into the downturned leg of the elbow 16. The tension of the 15 spring 22 may be so adjusted that the water rises to any desired level in order to accumulate sufficient head to open the valve, thus readily adapting the system to changes in steam pressures. The bore of the nipple 24 20 is so small that the escape of steam therethrough after the air has been expelled from the radiator will be so slight as to be negligible.

I claim as my invention—

25 1. A trap return connection for radiators having in combination, a body having a

chamber whose outlet is higher than its inlet, the chamber having an air vent through an upper wall; an elbow connected with the chamber and having its remoter leg directed 30 downward, an outwardly-opening spring-seated valve within the vertical arm of the elbow; a stem carrying the valve and being vented therethrough.

2. In combination, a chambered body, its 35 chamber having openings in its upper and lower walls; an elbow connected with the chamber and having a down-turned leg, with an outwardly - facing valve - seat, a valve stem located on the vertical axis of the down-turned leg and extending through and in threaded engagement with the elbow wall, and having a duct opening through its inner 40 end and laterally adjacent its upper end, a valve loosely fitting on the stem and adapted 45 to the valve-seat, and a spring reacting between the valve and a shoulder at the inner end of the stem.
